APPARATUS FOR SURFACING ROOFING

Jules L. Wettlaufer, Belmont, Mass.

Original application March 28, 1928, Serial No. 265,484. Divided and this application December 31, 1930. Serial No. 505,717

3 Claims. (Cl. 91—43)

This is a division of my co-pending application Serial No. 265,484, filed March 28th, 1928.

This invention relates generally to mixing devices for producing various mixtures of solid 5 granular or comminuted materials, and finds one particular adaptation in the prepared roofing industry wherein mineral materials are employed in the process of manufacture. Roofing prepared in this way generally comprises a foundation 10 of felted fibrous material which is saturated in sheet form with waterproofing material of the character of asphalt, and is also provided with a waterproof and weatherproof coating of asphalt on one or both surfaces thereof, and in some instances on the edges thereof which are exposed 15 to the weather when the roofing is applied on a roof. The waterproof coating on the surface of the sheet which is to form the exposed portion of the finished roofing product is usually provided 20 with a wearing surface of grit, such as crushed slate or similar material, in order to protect the waterproof coating and to provide a finishing surface for the product.

Granular material which has been found suitable 25 for this purpose lends itself very well to the production of roofing material of this character having a wide variety of colors or color arrangements on the exposed face thereof.

At the present time there is a considerable demand 30 for this type of roofing finished in surfacing material of other than a solid color. Attempts have been made to produce roofing surfaced with various colors but the general result has been that when the roofing material is laid up 35 on the roof the various colors appear to the eye of the observer either in mathematical regularity or they are otherwise distributed over the roof as to be displeasing to the eye, or in any event do not meet the demand which now prevails for a 40 roof of a number of colors blended into one another or distributed over the roof in such a haphazard and irregular fashion as to effect a harmonious and pleasing color arrangement with no patterning or striping of the colors at one or more 45 places along the roof.

It will be understood that prepared roofing of the type here referred to may be either in the form of sheets or as individual shingles, or as the so-called strip shingles of commerce.

50 Strip shingles and individual shingles which can be laid so as to produce a finished roof meeting the requirements of a harmonious and artistic color arrangement as above noted, are being manufactured today, but in order to avoid the 55 objections already described it is necessary to

produce a series of separate stocks of the shingles, the color arrangement in the shingles of each stock being either wholly or partly different from that of the shingles of the other stocks, and the shingles of the separate stocks being thereafter 60 assembled in accordance with a predetermined plan so that when they are taken by the workman laying the roof, from the package containing them, and laid up in regular order, the finished roof will have the desired haphazard arrangement 65 of the colors. The necessity for making separate runs for producing the shingles of the different series, is open to objection, since it entails a large amount of storage space for the accumulation of the stocks which are to be mixed, 70 and furthermore the assembling of the shingles of the various series requires additional labor and other expense.

The primary object of my invention resides in the provision of mechanism which can be very 75 readily adopted in the manufacture of prepared roofing and by means of which colored mineral granules or other surfacing material may be combined and applied to the roofing sheet in such a way that successive shingles or strip shingles 80 having varying arrangements of color thereon, may be cut from the sheet and immediately packaged without the necessity for assortment and re-assemblage.

With these and other objects in view, my invention 85 consists in the organization, arrangement and combination of elements as will presently appear, and for a more complete understanding of the same and the advantages thereof, reference may be had to the following more detailed description and to the accompanying drawings, in which,

Figure 1 is a view in elevation of one form 95 of apparatus in which the present invention may be embodied.

Figure 2 is a plan view of part of the mechanism shown in Figure 1.

Figure 3 is a vertical view in section taken along line 3—3 of Figure 1, through one of the compartments for containing the mineral grit to 100 be applied to the roofing sheet and the means for delivering the material from the hopper to the sheet.

Figure 4 is a detail view in plan of mechanism which may be employed in the compartments in 105 accordance with my invention.

Figure 5 is a view similar to Figure 4, but showing certain of the mechanism shown in Figure 4, partially removed from operative position.

Figure 6 is a collective view in detail, of cer- 110

tain of the devices appearing in Figures 4 and 5.

Figure 7 is a view similar to Figure 4, showing the parts in another position.

Figures 8, 9 and 10 are detail views in plan 5 of various arrangements of certain of the parts that may be employed in carrying out my invention.

Figure 11 is a view showing a baffling plate that 10 may be employed in conjunction with the invention.

Figure 12 shows an arrangement for securing certain ornamental effects in accordance with the invention.

It will be understood that the sheet of felt 15 forming the foundation of the roofing material, saturated to the extent desired with waterproofing liquid such as molten asphalt and coated on one or both faces thereof with high melting point blown asphalt, is fed with the sticky asphalt on the surface thereof, continuously beneath the mechanism for applying the surfacing material to the surface of the sheet which is to form in the finished product the exposed face thereof. Generally the opposite surface of 20 the sheet when provided with coating, is covered with some non-adherent material such as finely powdered mica or talc, although it is within the contemplation of my invention that after one surface of the sheet has been covered with the 25 granular surfacing material the sheet may be reversed by any suitable mechanism so that in the further travel thereof it will present its opposite surface to a surfacing mechanism similar to that employed in the first instance so as to 30 cover the opposite side with granular material which may be of a character similar to or different from that on the first side and with a color arrangement either duplicating that on the first side, or different therefrom.

40 It will also be understood that after the surfacing material has been applied to the sheet the latter is fed around suitable pressure rolls to cause the granular substance to be more firmly imbedded in the asphalt coating, whereafter the 45 sheet may be formed into rolls of desired size or cut into individual or strip shingles of any suitable or desirable shape.

Referring in detail to the drawings, S indicates 50 a section of asphalt saturated and coated roofing felt as it is proceeding beneath the surfacing mechanism. In the production of this type of roofing it is generally the common practice to deposit the granular mineral surfacing in such way as to form a plurality of ribbons of various 55 colors or shades upon the sheet, which, in the case of strip shingles cut transversely from the sheet, corresponding to tabs of the shingle strip. In the mechanism shown on the drawings, three distinct streams of color are deposited so as to 60 produce three distinct ribbons extending longitudinally of the sheet, these ribbons or stripes of color being of approximately equal width, but obviously, the number, as well as the relative widths of the stripes, may be varied as desired. 65 Each of these streams is produced by one of the series of compartments A, B, C, each of which is divided off into separate compartments wherein a constant supply of mineral of the desired 70 primary colors is maintained.

The individual compartments are indicated in 75 each series by the numerals 1, 2, 3 and 4, after the letter representing the respective series.

The compartment series are preferably formed as elongated cylindrical containers provided on 75 the interior thereof with vertical partitions 40,

extending at right angles to one another so as to form separate compartments with the compartments, the lower end of the partitions being substantially in alignment with the lower end of the compartments. Obviously, however, the 80 containers may be divided into a greater or lesser number of compartments by the employment of partitions suitably positioned therein.

In accordance with my invention, the granular surfacing material in one of the compartments 85 in each series, may be combined and intermixed as will be more fully explained hereinafter, with granular material contained in one or more of the other compartments in the same series. In one embodiment of my invention, I associate with 90 each of the series of compartments a rotatable blending disk 42 which is so constructed as to be capable of producing, when used in conjunction with certain control plates as will be more fully explained, various mixtures of mineral from 95 the compartments composing each series. In the form shown, the blending disks 42 may be simply flat circular plates of metal or other suitable wear-resistant material, and, as illustrated in Figures 4 to 7, may be formed with an arcuate series of perforations 43 and a plurality of radial 100 series of openings 44.

The blending disks 42 are each mounted for rotation upon an inwardly directed bearing flange 45 formed at the upper end of a funnel shaped 105 chamber 46 which is adapted to receive the mineral withdrawn from the corresponding compartment series for delivery to the coated sheet.

In order to effect rotation of the blending disks 42, the latter are each provided with a hub portion 47 suitably connected to a rotatable shaft 48 so that upon rotation of the latter the disk 42 connected therewith will be caused to rotate. The 110 shafts 48 may be journaled in suitable supports and connected in any convenient way with a 115 source of power. As shown, the connections of the shafts with the source of power may be through the gears 49 fixed to the respective shafts and meshing with similar gears 50 which may be connected with a main drive shaft (not shown). The 120 connection of the shafts 48 with the main drive shaft is preferably such that independent control 125 may be exercised over the speed or direction of rotation of each of the shafts, so that any one or more of the shafts may either be disconnected at will or independently manipulated so as to increase or decrease the speed thereof in relation to the speed of rotation of the other shafts. Conveniently, and with advantage, in many instances, 130 these connections may, if desired, include suitable variable speed devices.

For the purpose of producing various predetermined mixtures of material from the compartments in each series, I employ in conjunction with the rotating discs 42, flat control plates 51, such as shown by way of example, in Figures 4 to 7, these plates being adapted for insertion below the compartments in each series, and when in position, fitting snugly against the lower ends thereof and being spaced slightly above the upper surfaces of the rotating discs 42, for a purpose to be more fully explained hereinafter.

Various styles of control plates are adapted 145 for producing different effects. In the forms illustrated in Figures 4 to 7, these control plates may be of quadrant, and in some instances of segmental shape, with their side edges converging at approximately an angle of 90° so that each plate will fit properly below the lower edge of the 150 compartments in each series. The outer edge

of each of the control plates may be provided with an upwardly extending lip 52, adapted to fit against the exterior surface of the outer wall of the compartments and with a handle portion 53 to permit ready insertion and removal of the plates. In order to facilitate the insertion of the control plates in the compartments and their removal therefrom, they may be formed with radial open-ended slits 55 for co-operation with vertical guide-
10 plates 56 fixed within each of the compartments adjacent the lower end thereof.

In order to relieve the disk and control plates from the bulk of the weight of material in each compartment, I may provide cone-shaped pans 15 54, fixed within each of the compartments at a suitable distance above the control plate therein.

As already indicated, the mineral of primary color in the various compartments in each series may be united and intermingled in such a way 20 as to produce a stream of granules, the composition of which may be varied depending upon the relative arrangement of the perforations in the blending disk and upon the style of control plate used in conjunction therewith. Thus, one arrangement by way of example, is shown in Figure 25 4, wherein one of the series of compartments, as for example series A, may have the separate compartments A1, A2, A3, A4 thereof, supplied with 30 granules of different colors, the arrangement here being such as to produce a mixture of approximately three parts of the material in compartment A3 and approximately one part of the material in compartment A2, with a periodic addition to this mixture of the mineral in compartment A4, the mineral in compartment A1 being 35 blocked out so as to form no part of the ultimate mixture delivered from this series of compartments. In order to effectuate this result there is 40 inserted in the compartment A1, a quadrant-shaped control plate 51a which blocks out entirely this compartment and prevents any of the mineral therein from dropping through any of the openings in the rotating disk 42 during the rotation thereof. In the compartment A2 there is 45 inserted a segmental control plate 51b, adapted to block out approximately two-thirds of the area of the surface exposed in this compartment by the perforations in the disk 42, during the rotation thereof. The compartment A3 in this 50 instance is provided with a control plate 51c of the same type as the plate 51b, but of lesser radial extent, the proportioning as shown, being such as to block out one-third of the area exposed in this compartment by the perforations in the disk 55 42 during the rotation thereof. In the compartment A4 a control plate 51d may be employed, this type of control plate being provided only with an arcuate slot 57 in the body thereof, so as to block out the radial series of perforations 44 in the rotating disk while the arcuate slot 57 registers periodically with the arcuate series of perforations 43 in the disk 42 during the rotation thereof. As will be apparent, during the rotation 60 of the disk associated with this series of compartments, there will be constantly formed a mixture of approximately 1 part of the material in compartment A2 with about 3 parts of that in compartment A3, and to this mixture there will be 65 added periodically the material from compartment A4, this addition occurring upon the registration of the perforations 43 in the disk 42 with the slot 57 in the control plate 51d of this compartment. Manifestly the effects may be varied 70 to suit the particular type of material to be pro-

duced by a judicious choice of control plates used in the various compartments.

In some instances, for example, it may be desirable to employ in each of the compartments in a series, control plates such as shown at 51d so that the material in the compartments will be discharged therefrom only upon the registration of the perforations 43 in the rotating disk 42 with the slots 57 in the respective control plates. In this case, as will be obvious, there will be a substantially periodic variation in the composition of the granular mixture delivered from this series. Thus, assuming that the compartment A1 contains a red mineral, the compartment A2 a green mineral, the compartment A3 a yellow mineral, and the compartment A4 a brown mineral, each of these compartments being fitted with control plates of the type shown at 51d, and the disk 42 rotating in a counter-clockwise direction, there will be delivered at one stage, for example, a solid red mineral, followed by a mixture of the green mineral with the red, the proportions of the green mineral constantly increasing and the proportions of the red mineral constantly decreasing until solid green mineral is delivered. Then, upon the entrance of the perforations 43 beneath the compartment A3, the green mineral will be constantly varied by increasing proportions of the yellow mineral in compartment A3 until a solid yellow mineral is delivered, whereupon during the further rotation of the disk the brown mineral from compartment A4 becomes mixed in gradually increasing quantity with the yellow mineral from compartment A3 while the proportion of yellow decreases until solid brown mineral is delivered, which is then varied by the increasing amounts of the red mineral in compartment A1 as the disk continues to rotate, and so on, the series of colors repeating itself in this order. Obviously the sequence in which the colors are delivered may be varied by reversing the direction of rotation of the disk or by storing the primary colors in the compartments or series of compartments in a different order. Furthermore, it will be apparent that the rapidity with which the change in the composition of the mixture delivered from the series of compartments may be effected, will depend upon the speed of rotation of the disk 42 in relation to the rate of travel of the sheet of roofing material, the more rapid the rate of rotation of the disk for a constant linear speed of the sheet, the shorter will be the period of the change, and vice versa. Hence, by connecting the shafts carrying the gears 50 with suitable variable speed mechanism, the speed of rotation of the disk may be varied as desired so as to increase or decrease the periodic change in the composition of the mineral delivered from the series of compartments. Where the mechanism is employed in the manufacture of strip shingles, the rate of rotation of the disk 42, may, if desired, be sufficiently rapid, in relation to the linear speed of the sheet of roofing base, to cause the mixtures of varying colors to be deposited on the sheet in successive areas corresponding substantially to the tabs of the finished shingle strip.

It will be understood of course, that the quantity of mineral delivered at any one time by a series of compartments, is governed by the size and disposition of the perforations in the blending disk relative to the openings in the co-operating control plates, and obviously, the parts must be so proportioned as to provide at all times a flow of mineral sufficient to cover the desired

area of the sheet, and where, as shown, a plurality of series of compartments are employed to surface a sheet of roofing base, substantially equal quantities are delivered from each series and the total quantity delivered from all the series should manifestly be ample to completely surface the entire width of the sheet during its progressive travel forwardly.

In actual practice, it frequently happens that the sheet of roofing slows down somewhat in its travel, due to delays at other points along the roofing machine, and not infrequently the travel of the sheet must be entirely stopped temporarily. It will be obvious of course, that under such circumstances, the perforations in the rotating disk 42 which are not covered or closed off by solid portions of the associated control plates, would continue to discharge mineral upon the surface of the retarded or halted sheet. The mineral thus accumulating while the sheet is not moving forwardly under normal speed would be wasted, for it would be very difficult to segregate the components thereof or thereafter distribute the same in the desired manner over the surface of the sheet. I provide means for taking care of such a contingency and for otherwise enabling the surfacing operation to be conducted under better control.

For this purpose, I provide mechanism including stop plates and means for moving the same to and from a position in which the flow of mineral produced by the associated rotating disk and control plates may be stopped entirely or diminished to any desired extent. In the form illustrated, this mechanism comprises stop plates 60 adapted to slidably fit within the space in each compartment between the upper surface of the rotating disk 42 and the lower face of the control plate therein. These stop plates are of quadrant shape and are provided with a plurality of radial and arcuate series of perforations 60a similar to those in the disk 42, but staggered with relation thereto in respect to the axial center of the compartment series so that when the stop plates are moved to the position shown in Figure 4, the perforations therein will be out of register with those in the rotating disk and consequently no mineral will flow from this series of compartments. On the other hand, when the stop plates 60 are in the position shown in Figure 7, (the control plates being omitted in this figure for the sake of clearness), the perforations therein will coincide with the openings in the disk and hence permit the mineral to flow therethrough. Between the open position of Figure 7 and the closed position of Figure 4, the stop plates may be caused to rest at intermediate positions in which the openings in the disk 42, will be more or less partially shut off.

In any event, however, the movement of the plates 60 to and from their respective positions, is accomplished by a mechanism preferably designed to move all the plates simultaneously. As shown in Figure 2, the arrangement comprises plates 61 adapted for operative connection with the stop plates of the compartments A1, A2, C3 and C4, and semi-circular plates 62a to 62d adapted for connection with the stop plates of a pair of adjoining intervening compartments. Thus, as shown, plate 62a is connected with the stop plates of compartments A4 and B1, plate 62b is connected with those of compartments A3 and B2, plate 62c with those of compartments B3 and C2, and plate 62d with those of compartments B4 and C1. The plates 61 and 62a-62d

are each provided with eccentric slots 64 within which are adapted to slide the pins 65 riveted or otherwise secured to ears 66 extending outwardly from the arcuate edge of each stop plate substantially at the mid-point thereof. The stop plates are also formed with radially extending open slits 67 adapted to embrace the guide plates 56 within the compartments so as to maintain the stop plates at all times in proper axial position. It will be seen that upon rotative movement of the plates 61 and 62a, b, c and d the pins 65 will slide within the eccentric slots 64 and cause the stop plates to be moved inwardly or outwardly depending upon the direction of rotation of the operating plates. The movement of the operating plates is effected by the sliding bars 70 and 71 mounted upon suitable supports and guided in their movement by the fixed pins 70a and 71a passing through elongated slots 70b and 71b formed in the bars near the ends thereof. Fixed at suitably spaced points along the bars 70 and 71 are a number of pins 72, adapted to slide, during rectilinear movement of the operating bars within closed slots 73 in the arms 74, projecting radially from the main body of the plates 61 and 62a-62d, the operating plates being pivoted as at 75 in any convenient manner. Movement of the bars 70 and 71 is effected manually by means of an operating lever 76 pivoted at 77 to a support 78 and passing through a slot 79 formed in the bar 80 connecting the bars 70 and 71 for unitary movement.

The operation of the foregoing mechanism will be obvious. Upon manipulation of the lever 76 the bars 70 and 71 may be caused to slide unitarily in one direction or the other, thereby effecting simultaneously rotation of all the operating plates and inward or outward movement of the stop plates connected therewith.

Hence, when the operator observes a slowing up in the speed of travel of the sheet being surfaced, the flow of mineral from all the series of compartments may be diminished by moving the lever 76 in the proper direction to cause the stop plates to move toward the position shown in Figure 4, and upon resumption of the normal rate of travel of the sheet, the lever 76 may be manipulated in the opposite direction so as to bring the stop plates to the relative position shown in Figure 7. It will be understood of course, that either in the full or partially open position of the stop plates, the quantity of mineral flowing from each series of compartments is substantially the same, while the sequence and relative proportion of mineral delivered from the respective compartments of each series is substantially preserved.

I have heretofore set forth various ways in which different effects may be produced by the mineral delivered from the compartments in one series, and obviously, by the employment of appropriate control plates in conjunction with the disks 42 rotating beneath the other series of compartments, these latter may be similarly made to deliver a flow of mineral composed of any desired mixture, either of constant or of a continually varying composition of the various minerals maintained in the separate compartments of the respective series. While the character of the flow from the said other series of compartments may be identical with that produced from the one already described so as to deposit entirely across the surface of the sheet, surfacing material of the same composition, which may either be constant or may vary as the sheet

progresses, it is preferred to make such a selection of colors in the compartments of the various series and to associate the control plates therewith and operate the driving connections, all 5 in such a way that the mixture delivered from each series will be more or less different from that delivered from any one of the other series, and the mixture from each series being either of constant or periodically varying composition, as 10 desired. Thus, where three compartment series are employed, the sheet may be surfaced with three stripes or ribbons of different colors or shades, and where the composition of one or more of the streams is caused to vary continually, 15 the corresponding bands or stripes on the sheet will vary more or less periodically in color. The color effects to be produced when laying up roofing shingles or strip shingles successively cut from a sheet of roofing material surfaced as described, will of course, govern the selection of the 20 minerals fed to the various compartments, and the type of rotating blending disk and control plates to be used therein.

As one illustration of a particular color effect 25 that might be produced in accordance herewith. I may employ in conjunction with each of the three series of compartments, a rotating disk having suitably spaced openings therein and co-operating control plates formed with slots or perforations so related to the openings in the disk that in one position of the disk the charge of mineral 30 delivered from each series will be composed of certain definite proportions of the mineral from certain of the compartments in said series. then 35 at a later stage in the rotation of the disk, the stream will be composed of the same or different proportions of mineral from the same and/or other compartments of the series, followed then by a mixture composed of either the same or still 40 different proportions of mineral from any one or more of the said and/or other compartments of the series, and then, if desired, by a still different mixture of desired composition from certain compartment in the series. the sequence in the 45 position of the charge thereupon repeating itself.

In Figures 8, 9 and 10 I show an arrangement of 50 rotating disks and co-operating control plates that may be used in the various compartment series to secure charges of the aforesaid character.

Referring to these figures, the blending disks 42a, 42b and 42c are adapted to be mounted for rotation in the compartment series A, B, and C, respectively. Within the compartments A1, B3, 55 there may be inserted control plates such as shown at 85: within the compartments A2 and B1 there may be placed control plates as shown at 86; within the compartments A3 and B2 there may be placed the control plates shown at 87; within the compartments A4, B3, C2 and C3, control plates as at 88; within the compartment C4 60 control plates as at 89 and in the compartment C1, a control plate as at 90. The rotating disks 42a, 42b and 42c are formed as shown, with a plurality of series of circular openings arranged 65 concentrically and located at various points circumferentially of the respective disks as shown. The control plates are formed with arcuate slots or perforations as indicated by the letter "a" following the numerals representing the respective plates, of greater or less radial dimension and at various radial distances from the axial center of the compartment series. Other of these plates, as for example those shown at 88 and 90, are not provided with slots as just described, but are segmental in shape and of greater 70 75

or less radial dimension from the outer edge thereof. The foreshortening of the control plates 88 and 90 and the arrangement of the slots in the control plates 8, 86 and 87, is such that desired proportions of mineral will be delivered 80 from selected compartments of each series during the continued rotation of the blending disk associated therewith, the mineral from the compartment or compartments of each series not desired in the mixture at any one stage during 85 the rotation of the disk, being blocked off.

In the particular arrangement illustrated, and assuming that the compartments A1, B1 and C1 contain red mineral, the compartments A2, B2 and C2 black mineral, the compartments A3, B3 and C3 green mineral, and the compartments A4, B4 and C4 brown mineral, and referring more specifically to Figure 8, it will be seen that with the disk 42a in the position shown in this figure, there will be exposed by the control plate 86 in the compartment A2, six openings in the disk, and by the control plate 88 in compartment A4, four openings in the disk, so that mineral will be discharged from these two compartments in the proportion of three parts of black to two parts of 100 brown, the openings in the rotating disk underneath the other compartments of this series being blocked out, by virtue of the fact that in this position of the disk none of the openings therein are in registration with slots in the control 105 plates in these compartments.

As the disk 42a rotates in a counter-clockwise direction through an arc of 90° it reaches a position wherein mineral from compartments A1 and A2 is blocked off by the control plates 110 therein, while the control plate 87 in compartment A3 exposes six openings in the disk and control plate 88 in compartment A4 exposes three openings in the disk, thus producing a mixture composed of two parts green and one part brown. 115 When the disk has passed through another 90° in its rotation, the black mineral of compartment A2 is blocked by the control plate 86, while control plates 87, 88 and 85 each expose three openings in the disk so as to form a mixture 120 of equal parts of red, green and brown mineral. Then, as the disk rotates through another 90° it reaches a position where the control plate 87 in compartment A3 exposes three openings in the disk and the control plate 88 in compartment A4 exposes six openings in the disk, thus 125 forming a mixture composed of one part green mineral, and two parts brown mineral. Thereafter, the return of the disk to the position initially referred to will effect repetition of the 130 above described cycle. It will be seen that substantially the same number of holes in the disk are exposed at all times during the rotation thereof, and consequently the rate of feed of mineral from the compartment series is substantially uniform. 135 It will be understood also, that as the disk continues in its rotation there will be a more or less slight blending of the successive mixtures produced at the various stages.

Similarly, rotation of the disk 42b of the compartment series B, in co-operation with the arrangement of control plates shown in Figure 9, will produce a stream, the composition of which is first one part green and two parts black, then 140 equal parts of green, black and brown, followed by two parts green and one part black, and then by three parts red and two parts green. Likewise the stream from the compartment series C may be composed successively of two parts 145 green and one part black, then equal parts of 150

green, black and brown, followed by two parts black and one part green.

- 5 The period of change in the composition of the mixture in the several streams will depend, of course, upon the rate of rotation of the blending disks 42a, 42b and 42c, and while in some instances the rate of rotation may be the same for the disks of all the compartment series, it is preferred, in order to produce a more harmonious effect on the roof, free from any appearance of patterning, to connect the shafts 48 for independent operation as heretofore described, so that while any of these streams may be composed of a mixture which changes and repeats itself relatively rapidly, any one or all of the other streams may be composed of a mixture in which the succession of the various mixtures repeats itself relatively slowly. Thus, the shaft of the compartment series A may rotate at 35 10 R. P. M., that of series B at 20 R. P. M., and that of series C at 28 R. P. M.

20 In this way, repetition in the arrangement of the colors transversely of the sheet is reduced to a minimum and the tendency towards splotchy or patterned effects on the roof laid with shingles cut from the sheet is thereby practically entirely eliminated.

25 The mineral discharged from each series of compartments flows through the funnel-shaped chambers 46 to the downwardly inclined chutes 80 for conveying the mixtures to the mixing chambers 81, in which are arranged series of inclined baffle plates 82 adapted to effect an intimate commingling of the minerals contained in each stream, the final mixture from the lowermost baffle in each chamber being deposited upon the sheet of coated roofing base travelling therebeneath. If desired, each of the baffle plates may be provided, as shown in Figure 11 with 30 shallow grooves or flutes extending transversely thereof and arranged to effect a lateral spreading of the stream of mineral so as to cause the components thereof to become more intimately mixed.

40 45 The rotating shafts 48 pass through stuffing boxes 83 in the walls of the chutes 80 and extend upwardly through the chutes and funnel chambers 46 for connection with the respective rotating disks 42. The funnels, together with 50 their associated chutes, may be removably mounted so as to permit lowering of the shafts to enable the disks 42 to be exchanged, or other parts to be replaced.

55 I have heretofore referred to the minerals in each of the compartments in a series as being composed of mineral of a single primary color, but it should be understood that in certain instances the minerals in these separate compartments may be composed of any desired mixture of minerals, which mixtures from the compartments in a series may then be combined as desired, by the use of appropriate control plates in association with the rotating disks.

60 65 Instead of depositing the mineral upon the sheet in steady streams so as to produce color bands substantially parallel to the longitudinal edges of the sheet, the streams as delivered from the mixing chambers 81 may be caused to oscillate to and fro by any suitable means, as for example by means of pipes or spouts 81a freely mounted for oscillation upon a shaft 81b and rocked upon the shaft by a rocker arm 81c carrying pins 81d on opposite sides of the spout and actuated by an eccentric disk 81e mounted on a shaft 81f. By 70 75 thus oscillating the streams before they reach

the sheet the minerals will be deposited in wavy or undulating bands instead of straight parallel bands, and by varying the amplitude of oscillation of the streams, various ornamental effects may be produced in addition to those which may be produced by the variation in colors as already described.

80 85 It will thus be seen that by my present invention I provide mechanism affording considerable latitude and flexibility of operation, and which is readily adapted to the production of composition roofing not only of any solid shade of mineral or predetermined mixture of minerals, but which is also adapted for surfacing a sheet with a plurality of stripes which may be of differently colored minerals, and the color of which may undergo more or less change as the operation continues so that successive roofing elements cut either lengthwise or crosswise of the sheet, may be packaged directly as they are delivered from the cutting operation without requiring them to be assorted and reassembled in order to produce when laid upon the roof, a harmonious association or blending of colors such as is now in great demand in the prepared roofing industry.

90 95 Having thus described several embodiments of my invention it will be evident to those skilled in the art that many and devious changes and modifications may be made therein without departing from its spirit or scope as defined by the claims 100 hereunto appended.

105 I claim as my invention:

110 115 1 The apparatus of the character described comprising a plurality of compartments arranged in a series, each of said compartments being adapted to contain a supply of granular roofing material of desired primary color and a perforated disk operatively associated with said series of compartments constructed for simultaneously discharging therefrom a plurality of streams from the different supplies of granular material contained in said compartments to form a continuous charge of a periodically varying predetermined mixture of the mineral in said compartments.

120 125 2 The apparatus of the character described comprising a plurality of compartments arranged in a series, each of said compartments being adapted to contain a granular roofing mineral of desired primary color, means for advancing a roofing sheet to be gritted under said compartments, means operatively associated with said series of compartments constructed for simultaneously discharging therefrom a plurality of streams from the different supplies of granular material contained in said compartments to form a continuous charge of a periodically varying predetermined mixture of the mineral in said compartments, and means for regulating the rate of flow of said charge in accordance with the rate of travel of the roofing sheet.

130 135 3 An apparatus of the character described comprising a series of compartments, each compartment in the series being adapted to contain mineral roofing granules of different primary colors, stationary control means associated with said compartments and having discharge openings of differential capacities and a perforated disc cooperating with said discharge openings for rotation therebeneath to simultaneously withdraw roofing granules therefrom in periodic succession.

140 145 4 An apparatus of the character described comprising a series of compartments, each hopper in said series being adapted to contain mineral

- granules of different character, control plate means having openings of predetermined and differential capacities situated beneath said compartments and a rotating perforated disc cooperating with said openings to simultaneously withdraw a plurality of streams of said minerals of different characters in cyclically varying proportions, means for thoroughly admixing the granules in said streams and applying the same to an advancing sheet of roofing. 5
5. Apparatus of the character described comprising a series of compartments, each of said compartments adapted to contain mineral roofing granules of different character, a plurality of control plates detachably and interchangeably associated with the said compartments and a rotating disc having openings cooperating with said control plates for simultaneously withdrawing a plurality of streams from said compartments in cyclically varying proportions, means for admixing the streams thus discharged and applying the same to an advancing sheet of roofing. 10
6. Apparatus of the character described comprising a series of compartments, each of said compartments adapted to contain mineral roofing granules of different character, means for simultaneously withdrawing streams of roofing granules from a plurality of said compartments, and means for continuously changing the ratio of the granules composed by said streams without substantially changing the aggregate volume of the granules of the total of said streams, and means 15
- for interadmixing the simultaneously discharging streams of varying composition and applying the same to an advancing sheet of roofing. 20
7. Apparatus of the character described comprising a series of compartments, each of said compartments adapted to contain mineral roofing granules of different character, means for simultaneously discharging streams of roofing granules from a plurality of said compartments, and means for cyclically varying the composition of one stream relative to the others without substantially changing the aggregate quantity of the plurality of streams being simultaneously discharged, and means for admixing the streams and applying the same to an advancing sheet of roofing. 25
8. An apparatus of the character described comprising a series of compartments, each of said compartments adapted to contain mineral roofing granules of different character, control means having openings of different capacities cooperating with said compartments, a rotatable perforated disc periodically registering with said openings provided by the control means and being adapted to simultaneously withdraw streams of roofing granules from a plurality of said compartments in periodic succession, the perforations in said disc and the openings provided by the cooperative control means being so related as to insure a substantially uniform rate of feed of the mineral from the series of compartments. 30
